(57) **CLAIM**

The ornamental design for a display screen with animated icon, as shown and described.

DESCRIPTION

FIG. 1 is a front view of a first image in a sequence of a display screen with animated icon showing the new design; FIG. 2 is a front view of a second image thereof; FIG. 3 is a front view of a third image thereof; and, FIG. 4 is a front view of a fourth image thereof.

The appearance of the animated icon transitions between the images shown in FIGS. 1-4. The process or period in which an image transitions to another forms no part of the claimed design.

The broken lines of uneven length show the display screen and form no part of the claimed design.
